[57]

ABSTRACT

Method of, and apparatus for, making a stitch-bonded fabric with thermoinsulating properties having sufficient strength in all directions, to make it possible to use said stitch-bonded fabric for outerwear. The fabric includes a base and transversely arranged weft threads and warp threads knitted through the base by a warp knitted weave.

In the method of the invention for manufacturing the product a weft system is fed parallelly into the operation point of the stitch-knitting machine together with a base, and at the said operation point the said weft system is knitted together by warp threads, thus being connected to the base.

In the apparatus according to the present invention a separating bar is mounted at the operating point of the stitch-knitting machine between the bits bar and the supporting comb.

METHOD OF, AND APPARATUS FOR, MAKING STITCH-BONDED FABRIC

The present invention relates to a method of and a device for manufacturing a stitch-bonded fabric on the ARACHNE type.

Products are known which comprise fibrous fleece as a foundation, said fleece being reinforced by longitudinal stitch-bonding of warp threads e.g. by chain stitch or tricot stitch. A method of manufacturing them is also known, in stitch-knitting machines, and stitch-knitting machines in which stitch-bonding of the fleece takes place are also known. This is made possible by the construction of needles and transversible latches, the needles thus closed by latches being not caught by the separate fiber of said fleece upon the passing of the needles therethrough. Moreover, this stitch-bonding makes possible a needle and latch motion in the direction of movement of the fleece at the phase of the passing of the needles therethrough.

Products are also known which includes transversely arranged weft threads gripping between the rib stitches and rib loops by a warp weave of bonded warp threads. A device is known for manufacturing said products, the principal part of said device consisting of a conveyor feeding weft threads arranged thereon at regular intervals into the operation mechanism of a stitch knitting machine, and of another conveyor which refills the weft system on the said first conveyor from a weft thread supply.

The disadvantage of the first said stitch-bonded fabric comprising a fibrous fleece consists in its insufficient strength in the transversal direction, while the disadvantage of the other said stitch-bonded fabric comprising weft threads consists in its relatively low thermoinsulating qualities.

The purpose of the present invention is to substantially mitigate the above disadvantages and to provide a method of making a stitch-bonded fabric of sufficient strength in all directions, such fabric having thermoinsulating properties which make possible the application of said stitch-bonded fabric for outerwear.

The product made by the method according to the present invention includes a base, transversely arranged weft threads, and warp threads knitted through the base by a warp knitted weave.

In the method of manufacturing the product a weft system is fed parallelly in to the operation point of the stitch-knitting machine together with a base, and at the said operation point the said weft system is knitted together by warp threads, thus being connected to the base.

In the device according to the present invention a separating bar is mounted at the operating point of the stitch-knitting machine between the bits bar and the supporting comb.

Further advantages and features will be apparent in the following specification and the accompanying drawings of illustrative embodiments of the invention.

In the drawings:

FIG. 1 is a view in perspective of the stitch-bonded fabric made by the method according to the present invention;

FIG. 2 is a diagram of the device for manufacturing the stitch-bonded fabric of FIG. 1; and

FIG. 3 is a fragmentary view in section of the operating point of the device according to the present invention.

The stitch-bonded fabric (FIG. 1) made by the method according to the present invention consists of a base 1, transversely arranged weft threads 2, and warp threads 3 which stitch-bond the base by a warp weave, e.g. chain or tricot weave, and which by this stitch-bonding simultaneously fasten the weft threads 2 to the base 1. Weft threads 2 are arranged on the product between the rib stitches 31 of the warp threads 3 and base 1 (FIG. 1). A needled and thus partially reinforced fibrous fleece can be used as base 1, or possibly a prefabricated woven or knitted fabric, or a layer of chemically produced materials, e.g. polyurethane. The product shown in FIG. 1 as an illustrative embodiment comprises a weft thread 2 in each course of warp threads 3. It is also possible, from the view of patterning, to omit weft thread 2 in certain courses.

The device according to the present invention includes a supply beam 4, from which there is unwound the base 1 by the pull of a withdrawing mechanism (not shown) in the direction of arrow S (FIG. 2). If desired, the base may be fed a simultaneous turning of supply beam 4 and the driving of the conveyor belt 5.

For the position feeding of the base 1 by conveyor belt 5 and supply beam 4, it is desirable to grip base 1 at the point of withdrawal 6 between the conveyor belt 5 and the supply beam 4, this it making possible to arrange the axis of rotation 7 of beam 4 in a recess 31 of its holder 8, so that said supply beam 4 is pressed by its own weight towards the conveyor belt 5.

Between cylinder 9, around which the direction of movement of base 1 is charged, and the operation point 10 of the stitch knitting machine the movement of base 1 is directed by a stationary guiding metal sheet 11, which holds base 1 in the plane extending between cylinder 9 and operating point 10 of the stitch-knitting machine.

The system of weft threads 2 is fed to the operation point 10 by means of a known conveyor belt 12, on which there are held the two ends of the separate weft threads 2. Conveyor 12 moves at a constant regular velocity synchronized with the velocity of stitch-bonding of the stitch-knitting machine by an accurate transmission coupled to the knitting machine. The lower branch 121 of conveyor 12 feeds the weft threads 2 to the operation point 10 in the direction T, while the upper branch of conveyor 12 returns, after the knitting-in of wefts 2 and the releasing of the grip or their ends, into its approximately horizontal part 122, where by known transversal conveyor (not shown) the weft threads 2 are laid into said first conveyor 12.

Base 1 and wefts 2 are fed to the operation point 10 parallelly between a stitch comb 13 and a supporting comb 14, the path of the weft threads 2 thus meeting with the base a short distance between the operation point. A separating bar 15 is mounted between the two said combs 13, 14, along the whole width of the stitch knitting machine. Base 1 is fed between the support comb 14 and the separating bar 15 and the wefts 2 are fed between separating bar 15 and stitch comb 13. It is possible to feed weft threads 2 and base 1 in opposite arrangement to operation point 10, i.e., base 1 between stitch comb 13 and separating bar 15. The product made in that manner is provided with weft threads 2

which are arranged between the purl loops of warp threads 3 and base 1.

Separating bar 15 is smooth on both sides, in order to enable base 1 as well as weft threads 2 to slide thereon with a minimum resistance. This bar 15 makes it possible to feed weft threads 2 at a higher velocity than base 1, this being necessary for the reliable fastening of weft threads 2 between the rib loop 31 and the base, as shown in FIG. 3.

Base 1 moves at a constant speed, whether in front of operation point 10 or upon being knitted into the finished product according to the present invention. The weft threads 2 move at constant speed until the moment at which they encounter a loop 32 drawn out by a needle (FIG. 3) which was formed by laying warp thread 3 by eye needle 17 on to knitting needle 16 and after movement of needle 16 in the direction U.

After encountering said loop 32, the movement of weft thread 2 is slowed down to the speed of base 1 and said weft thread 2 advances in permanent contact with said loop 32 until back movement of knitting needle 16, which penetrates base 1 and closes weft thread 2 between the rib stitches 31 and base 1, whereupon the ends of weft threads 2 are released by conveyor 12. Thus, a regular arrangement of weft threads 2 on the product is secured. If the distribution of weft threads 2 is to be performed according to a pattern, as already mentioned in the description of the product according to the present invention, then the weft threads 2 are laid upon conveyor 12 in accordance with such pattern.

Although the invention is illustrated and described with reference to a plurality of preferred embodiments thereof, it is to be expressly understood that it is in no way limited to the disclosure of such a plurality of pre-

ferred embodiments, but is capable of numerous modifications within the scope of the appended claims.

What is claimed is:

1. A method of manufacturing a stitch-bonded fabric which includes a fibrous fleece base including transversely laid weft threads and warp threads knitted through the base by a warp knitting weave, comprising simultaneously conveying in parallel relationship but at different speeds to the operation point of a stitch-knitting machine, on the one hand, a system of weft threads and, on the other hand, a fibrous fleece base, and connecting said system of weft threads to the base at said operation point by bonding them with warp threads, the speed of feeding the system of weft threads being higher than the speed of feeding the fibrous fleece base.

2. A device for manufacturing a stitch-bonded fabric which includes a fibrous fleece including transversely laid weft threads and warp threads knitted through the base by a warp knitting weave, comprising a stitch-knitting machine, means for simultaneously conveying in parallel relationship but at different speeds to the operation point of the stitch-knitting machine, on the one hand, a system of weft threads and, on the other hand, a fibrous fleece base, the speed of feeding the system of weft threads being higher than the speed of feeding the fibrous fleece base, means for connecting said system of weft threads to said base at said operation point by bonding them with warp threads, a separating bar, and a supporting comb, all arranged at the operation point of the stitch-knitting machine, the separating bar being disposed between the two combs.
